Specification for Design.

Patented Nov. 24, 1914.

Application filed June 1, 1914. Serial No. 842,323. Term of patent 3½ years.

To all whom it may concern:

Be it known that I, CHARLES A. SCHWARTZ, a citizen of the United States, residing at Richmond, county of Contra Costa, and State of California, and whose post-office address is Box 472, Richmond, California, have invented a new, original, and ornamental Design for a Vehicle-Tire, of which the following is a specification, reference being had to the accompanying drawing, forming part hereof wherein—

Figure 1 is a cross-sectional view, and

Fig. 2 is an elevation of a pneumatic tire made in keeping with my design.

I claim:

The ornamental design for a vehicle tire, as shown.

In testimony whereof I affix my signature in the presence of two witnesses.

CHARLES A. SCHWARTZ.
